(57) **CLAIM**

The ornamental design for a connector for a signboard carrier, as shown.

DESCRIPTION

FIG. 1 is a perspective view of the connector for a signboard carrier embodying the present invention;

FIG. 2 is a front elevational view of the connector for a signboard carrier;

FIG. 3 is a rear elevational view of the connector for a signboard carrier;

FIG. 4 is a side elevational view of the connector for a signboard carrier;

FIG. 5 is an opposite side elevational view of the connector for a signboard carrier;

FIG. 6 a top plan view of the connector for a signboard carrier; and,

FIG. 7 is a bottom plan view of the connector for a signboard carrier.

In the drawings, the broken lines represent features of the design forming no part of the claim.
